UNITED STATES PATENT OFFICE.

FRANK L. LANZY, OF CLEVELAND, OHIO, ASSIGNOR TO THE CHAMPION SPRING COMPANY, OF CLEVELAND, OHIO, A CORPORATION OF OHIO.

BEDSPRING STAY DEVICE.

Application filed June 10, 1926. Serial No. 115,000.

This invention relates to bedspring stay devices of the type designed to brace the border rods or wires against the objectionable lateral swaying of the springs upon their base. It is an object of my invention to apply a pivoted link mechanism to a bedspring made up of a series of coiled springs and more especially to such springs of the double-deck type, though the mechanism 5 may well be used for bracing coiled springs of the single-deck type, as will be readily understood.

It is my purpose in providing my improved stay device to mount the same upon 15 a base having elements extending in a direction at right angles to the length of the bedspring and also in a direction parallel to the side border wires, so that my improvement will serve to brace the springs to some 20 extent lengthwise of the bed as well as laterally. To do this I provide base connections with certain side bars of the springs and also with cross bars thereof. It is a further object of my improved device to mount the 25 same upon a horizontal base, or one that is in the plane of the bedspring bottom.

It is a particular object of my device that the said mechanism when in operation shall 30 not resist vertical movement of the springs or of the border wire attached thereto, but will be effective in resisting lateral movement of the springs relative to the bedspring base. It is a further object of my improved 35 device to provide an effective bedspring stay device that may be readily mounted upon bedsprings whose side bars may not be mounted on a plane substantially lower than the bottom of the coils, as well as those having the coils lowered below the plane of the 40 side bars.

With these and other objects of my invention that will appear as the description proceeds, I have embodied my inventive idea in the structure and combination of 45 parts hereinafter fully described, recited in the appended claims, and illustrated in the accompanying drawings, in which—

Figure 1 is a perspective view of the device shown as a unit detached from any 50 frame;

Figure 2 is a side elevation of the device mounted upon a bedspring adjacent the side bar and attached to the border wire which is shown in section; and

Figure 3 is a plan view of the device to-

gether with four adjacent spring coils and showing certain connected parts in section.

I have shown my improved device applied to a bedspring having doubledeck coils 5 supported upon cross bars 6 which are usually mounted in edge-wise position in the frame of the bedspring, and upon certain wide and stronger cross bars 7 which are often used intermediate the ends of the spring where the weight and consequent 60 strain is apt to be greatest. The upper ends of the coils 5 may be cross braced by coil springs 8 by plain wire, or by cable connections, if desired. Intermediate straps or wires 9 may brace the intermediate portions 65 of the coils 5.

The side bar 10 of angle iron is shown as 70 affording support for the outer row of coils, and has attached thereto ends of the cross braces 6 and 7, as well as serving for attachment of my stay device. About the outer 75 rows of spring coils 5, the border wire or rod 11 extends, and is attached to the upper spiral of each coil independently, usually by means of a wire strand 12 encircling the 80 strand and rod. Intermediate a pair of outer coils my stay device is usually mounted, and includes a relatively long locked lever 13 whose outer end is secured to the border rod 11 by suitable attaching 85 means, such as a loop 14 surrounding the rod and having outwardly bent ears 15 receiving therebetween the outer end 16 of the lock lever, the latter and the said ears being riveted or bolted together. 90

My stay device is preferably mounted upon a T-base formed of strap iron bars 17 and 18, the former extending in the direction of the length of the bedspring and having its ends 19 bent inwardly into parallelism for suitable attachment to cross bar 6 or to the cross bar 6 and one of the stronger bars 7. The strap 18 has its ends bent at right angles to the main portion, one of them 20 being riveted or otherwise secured to an intermediate portion of strap 17 and the opposite end 21 secured directly to the side bar 10. The cross bars 7 may be formed of angle iron and so positioned that its uppermost arm, as well as that of the side bar 10 shall be horizontal, the arm 22 serving to support thereon the outer row of coils 5, and receiving there-under the outer ends of the bars 6 and 7, and the bent ends 21 being riveted to the vertical arm 23. 105 110

The above arrangement of the T-base provides a very stable foundation for my improved stay device, which will now be explained in detail. Spaced a short distance 5 from the ear 20 two links 24 and 25 are pivoted at 36 to the strap 18, as shown clearly in Figs. 1 and 2. These links are of substantially equal length and are intended to swing loosely upon said common 10 pivot. At a point nearer the end 21, is securely mounted upon strap 18 a standard 26 fixed to said strap and in a position substantially at right angles to 18 and extending towards the lever 13. The outer end 15 of the link 24 is pivoted at 27 to the inner end of the lever 13, and the outer end of link 25 is pivoted at 28 to an end of a link 29 whose opposite end is pivoted to the lever 13 at 30, a point somewhat remote from 20 pivot 27.

The outer end of the standard 26 has pivoted thereto an end of a link 31 whose opposite end is pivoted at 32 to an intermediate point of link 29. This pivot 32 is ordinarily somewhat nearer the pivot 30 than the point 28, but this position may be changed depending upon the height of the coils used in the bedspring to which my improved device is applied, and upon lengths 35 of the links with which the lever is provided. It is obvious that the length of parts 26 and 31 may be varied to adjust the height which the border rod 11 is intended to assume in its higher and lower positions, and the said variation is contemplated.

The arrangement of the parts described above provides movement of the end 16 of the lever 13 toward and away from the pivot 36; that the links 24, 25 and 29 with the inner end of the lever form in effect a lazy-tongs device for said movement. The entire device comprising parts 13, 24, 25, 29 not only is adapted to move toward and 45 away from 36, but also may swing as a unit upon said pivot 36, unless other means is provided for controlling such movement. For the latter purpose the link 31 directs the lazy-tongs in such swinging movement, 50 so that the loop 14 is controlled and limited to a substantially vertical direction when the bedspring is in operative position, but is prevented from a lateral movement, so that the border wire 11 and the springs attached thereto are locked against the undesirable swaying movement of the upper portion of 55 the springs.

In addition to the control afforded by the improved stay device so far described, I 60 provide by arrangement of parts disclosed, a limit for the vertical movement of the loop 14 for its extreme upper position and lowest position, so that the bedspring may be lifted by means of the border wire without straining the coiled springs, and no in-

jury will be done to the bedspring by compressing the upper frames thereof for shipment. For this purpose, it will be noted that the lever 13 will strike the upper end 35 of the standard 26 when the lever lowers to its lowest position, contacting 35 at about the point x . On the opposite movement to the upper limit, the point y of the lever 13 will contact the end 34 of link 31, and thereby lock the device against further upward movement. It is to be understood that the standard 26 is fixedly secured by rivets 33 to the base member 18.

My improved stay device is rendered very stable by the base 17-18 which is securely attached to the bars of the lower frame of the bedspring, and thereby affords strong and efficient support for the pivoted stay members. It is also adapted to mounting upon bedsprings whose bars 10, 6 and 7, are 85 in a common plane, as well as the form of structure in which bar 10 is on a higher plane than 6 and 7. It is evident that my device may be readily applied to other forms of bedsprings than that here illustrated, it 90 being only essential that the bedsprings shall be provided with a series of coil springs and a border wire about the upper ends of the outer row of springs, a suitable base or foundation for the springs and this 95 device being, of course, necessary. The T-base is found to be especially desirable, but the stay device may evidently be mounted upon other base structure.

Other details of my improved device may 100 be modified without departing from the inventive idea of the same.

Having disclosed an illustrative embodiment of my invention, what I claim and desire to secure by Letters Patent is,—

1. In a bedspring, the combination of a bottom support for a series of coiled springs, a border wire connected to the upper ends of said springs, a lock lever pivotally connected at its outer end to said border wire, 110 a lazy-tongs device comprising three links and an inner portion of said lever, pivoted to said support and serving to extend the lever away from and towards the support, and means connected to the support at a 115 point remote from the pivot of the lazy-tongs, and to the latter, to limit and control the movement of the lever.

2. In a bedspring, the combination of a bottom support for a series of coiled springs, 120 a border wire connected to the upper ends of said springs, a lever connected at its outer end to said border wire three links and an inner portion of the lever comprising a lazy-tongs device pivotally connecting the inner 125 end of the lever to the support and serving to extend the lever away from and toward the support, a standard secured to the support remote from said pivotal connection, and a link pivotally connecting the upper 130

end of the said standard and the said lazy-tongs.

3. In a bedspring, the combination of a bottom support for a series of coiled wire springs, said support including a T-base, a lock lever having its outer end pivoted to the border wire of the bedspring, link mechanism pivotally connecting spaced points of the said lever to a single point of the said 10 T-base, and link means pivotally connecting the said base with said mechanism, for limiting the movement of the latter on said single point of the T-base.

4. In a bedspring the combination of a bottom support for a series of coiled springs, a pair of upstanding and downwardly-converging links pivotally connected to a unitary point on said support, a part pivotally connected to the upper end of one of said 20 links and having an outwardly-extending portion, a border wire connected to the upper ends of said springs and to said extending portion, a third link connecting the outer end of the other of said upstanding links 25 and a point of said part remote from its connection with the first said link, and means for limiting the lateral swinging of the device on its unitary pivot transverse of the bedspring.

30 5. In a bedspring, the combination of a bottom support for a series of coiled wire springs, said support including a base member of T-form, a lock lever having its outer end pivoted to the border wire of the bed- 35 spring, a pair of upstanding links pivotally united at their lower ends at a common

point on said base member, one of said upstanding links being pivoted to the inner end of the lever, another link pivotally connecting said lever at a point spaced from 40 its end with the outer end of the other upstanding link, and means connected with said pivotally connecting link for limiting the rearward movement of said links and the lever carried thereby.

45 6. In a bedspring, the combination of a bottom support for rows of springs and including a T-base, a pair of upstanding links pivotally connected at a common point on the main element of the T, a lock lever having its outer end pivoted to the border wire of the outer row of springs, a connecting link pivoted at its ends to the outer end of one of said upstanding links and to an intermediate point of said lever, respectively, and the outer upstanding link pivoted directly to the inner end of the lever, both upstanding links being mounted on the same side of the lever and main element, a standard fixedly secured to said main element of the base, 50 and means pivotally connecting the outer end of said standard to an intermediate point on said connecting link, whereby the border wire will be limited in its upper movement by the lever striking the pivotally connecting 55 means adjacent its point of attachment with the connecting link, and will be limited in its downward movement by striking the upper end of the standard.

60 In witness whereof I have hereunto set 70 my hand this 8th day of June, 1926.

FRANK L. LANZY.
